UNITED STATES PATENT OFFICE.

MICHAEL C. RYAN, OF PHÆNIX, NEW YORK, ASSIGNOR TO JAMES HOMER BETTS, OF NEW YORK, N. Y.

ILLUMINATED SIGN.

No. 922,958.

Specification of Letters Patent.

Patented May 25, 1909.

Application filed June 1, 1908. Serial No. 435,996.

To all whom it may concern:

Be it known that I, MICHAEL C. RYAN, a citizen of the United States, residing at Phoenix, Oswego county, New York, have invented certain new and useful Improvements in Illuminated Signs; and I do hereby declare the following to be a full, clear, and exact description of the invention, such as will enable others skilled in the art to which it appertains to make and use the same.

This invention relates to certain improvements in signs, and relates more particularly to the lamp boxes of illuminated signs; and the objects and nature of my invention will be readily understood by those skilled in the art in the light of the following description of the accompanying drawings illustrating what I now consider the preferred embodiment from among other forms and arrangements within the spirit and scope of my invention.

An object of the invention is to provide certain improvements in illuminated signs, such as electric flash light or intermittent signs used for display or advertising purposes, whereby such signs can be readily knocked down to occupy a relatively small space for packing or shipment, and can be easily set up or assembled and locked or secured in operative condition.

A further object of the invention is to provide certain improvements in construction, arrangements and formations of parts, whereby an improved and highly efficient lamp or light box or inclosure will be produced adapted for use in or as an illuminated sign.

The invention consists in certain novel features in construction and in combinations of parts as more fully and particularly set forth and specified hereinafter.

Referring to the accompanying drawings, forming a part hereof:—Figure 1, is a perspective view looking at the rear of the sign set up or assembled. Fig. 2, is a vertical cross section taken through the sign. Fig. 3, is a horizontal longitudinal section. Fig. 4, is a vertical cross section showing modified means for detachably securing the top and bottom plates to the frame or front. Fig. 5, is a perspective view showing the elements or members of the sign knocked down or folded flat.

In the drawings, 1, is the front plate or frame of the sign and can be made of any de-

sired shape, form or configuration. In the specific example illustrated, this front plate is in the form of an open flat rectangular frame adapted to receive the sign or display sheet or plate 2, having transparent letters or other display characters or representations to be illuminated by an electric or other light placed behind said sign. This sign is usually secured to and fits against the rear face of the front 1, and extends across and closes the opening of the front 1. The sign can be formed in any desirable manner of any desirable material and is usually opaque except for the letters or other representations which are to be displayed at the front 70 by a light at the rear thereof.

A light or lamp box preferably forming or constituting a reflecting inclosure, is arranged at the rear of the front 1, and is removably coupled or otherwise secured thereto. In the specific example illustrated, this inclosure consists of two side or top and bottom pieces 3, and a single back piece 4, together with means for detachably holding or locking the same together. The back piece 80 4, can be formed of a single length or strip of flexible sheet metal, and when the device is assembled or set up this sheet forms the concaved rear wall of the inclosure curving from the rear face of one vertical side or end bar of 85 the front to the rear face of the opposite side or end bar thereof, and in width greater than the vertical width or height of the front opening or the sign closing the same. This rear wall or sheet can be removably secured to 90 the front by or through the medium of suitable means. For instance, I show the end edges of the sheet removably fitted in inclined sockets or grooves 40, opening through the rear faces of the vertical ends of the front 95 and arranged longitudinally of said ends.

The side or top and bottom pieces 3, are usually similar in form and construction, and each can be composed of a segmental sheet metal plate, and of a size to engage the longitudinal edge of the concaved back and close the opening between the frame and said back. Each side plate is preferably formed with a flange 30, along its curved edge to fit the outer convexed surface of said back sheet. Each piece or plate 3 along its straight edge, is adapted to be detachably secured to the front 1, in any suitable manner so that said side plates will form the top and bottom walls of the inclosure. For in-

stance, I show the straight edge of each plate 3, deflected or bent laterally to form the longitudinal securing flange or edge 31, deflected from the plane of the plate in a direction opposite to the direction in which the flange 30, extends from the plate. The securing flanges 31, are adapted to removably rest flat against the rear faces of the horizontal bars or upper and lower portions of the front 1 and to be removably held thereto by turn buttons, hooks or projections 32, confined or secured to said frame bars, so that when the plates 3, are in their normal horizontal positions with the flanges 31 engaged by said projections 32, and with the plates engaging and bearing against the edges of the back, it will be impossible to remove said plates unless the projections 32, are swung from over the flanges 31, or unless the back 4, be removed.

In assembling the parts, the back can be first placed in position with its end edges fitted in the inclined grooves 40, which are so arranged as to maintain the back in its bowed or concaved position. The side plates 3, can then be placed in position with their curved edge flanges 30, lapping the outer convexed face of the concaved back, and the projections 32, can then be swung over securing flanges 31, to lock the side plates to the front frame.

Suitable means can be provided to hold the two side plates in locked position and against the longitudinal edges of the back 4. For instance, I show a contractile spring lock, wire or clamp 5, extending across the rear face of the back and having opposite end hooks, jaws or feet 6, fitting over the opposite side plates 3, and holding them to the back and if so desired having inbent extremities 7, entering perforations in the said plates 3. This spring clamp can be easily applied to or removed from the inclosure in setting up or in knocking down the same. The inclosure can be formed at any suitable points with openings for the passage of the wires to the electric light adapted to be arranged within the inclosure, and to receive the light holding bracket or fixture. For instance, I show the back 4, formed with a notch to constitute opening 8, and one or both side plates can have openings 9, for this purpose.

If so desired, the side plates can be removably confined to the front by other means than the hooked projections 32, whether such projections be fixed or in the form of turn buttons. For instance, the longitudinal securing flanges 33, might be arranged at an acute angle with respect to the plane of the plate (see Fig. 5), and adapted to removably enter sockets or grooves 34, arranged longitudinally of the upper and lower bars of the front frame and opening through the rear face and transversely inclined. In this arrangement, the inclined

flange or edge 33, is inserted in a groove 34, by holding the body of the plate inclined away from the adjacent longitudinal edge of the back 4, and when inserted the plate is swung down to its operative position against and lapping the back 4, to hold the same in position. When the end plates are in operative position, they can be removed, only by swinging the same away from the back 4, to permit removal of the inclined flanges 33, from the inclined grooves 34.

The sign sheet or plate can be removably arranged at the rear face of the front within the inclosure formed by the back and side pieces, and can be held to position by the end portions of the back sheet and by the side plates in a manner which will be readily understood by those skilled in the art.

The device can be packed in a small compass for shipment, when knocked down, as the front is a flat frame, the back when released straightens out as a flat sheet, and the two side pieces are also flat sheets with very short flanges, while the spring clamp or hook occupies but a small space and rests on the flat sheets lying on the front.

It is evident that various changes or modifications might be resorted to, that features might be omitted or devices added without departing from the spirit and scope of my invention and hence I do not wish to limit myself to the exact construction disclosed but consider myself entitled to all such changes as fall within the limits of the appended claims.

What I claim is:—

1. In an illuminated sign, in combination, a front frame having sockets at its rear face, a back having its ends inserted in said sockets, side plates removably lapping said back and removably confined to said frame, and spring means engaging said plates and removably holding the same to said back.

2. In an illuminated sign, in combination, a front frame, and a knock-down inclosure behind the same comprising a back, side plates removably lapping said back, means removably confining said plates to said frame, and a removable tie between said plates.

3. In an illuminated sign, in combination, a front frame having sockets at opposite portions of its rear, and a knock-down lamp inclosure carried by and arranged in rear of said frame and comprising a flexible back sprung from normal flat position and at its ends inserted in said sockets and held bowed.

4. In an illuminated sign, in combination, a front frame at its rear face having means for connecting lamp box plates thereto, a lamp-box bowed when set up and adapted to be flattened out for packing, removable side plates fitting the opposite edges of said back, and a spring device extending between said side plates and having lateral ends remov-

ably lapping over said plates and normally holding them to the back.

5. In an illuminated sign, in combination, a front frame having means for coupling a lamp box to the rear face thereof, and a knock-down lamp box comprising a back, removable side plates flanged to removably overlap the back, and a spring arranged transversely of the back and having its opposite ends yieldingly overlapping the side plates and holding them to the back.

6. In an illuminated sign, in combination, a front frame, a back coupled to said frame, side plates removably fitting the opposite 15 side edges of said back, means removably coupling the front edges of said plates to said frame, and a contractile spring connection between said plates and removably and yieldingly holding the same to said back edges.

7. In an illuminated sign, in combination, a front display-sheet-receiving frame, a back coupled to said frame, side plates at their front edges removably coupled to the rear of 25 said frame, said plates removably fitting the opposite side edges of said back, and means arranged at the exterior of said back and removably engaging said side plates to hold the same in set up position fitting said back.

30 8. In an illuminated sign, in combination,

a front display-sheet-receiving frame at the opposite side and end portions of its rear face having means for connecting the front edges of lamp box plates thereto, said means including a plate-edge-receiving elongated 35 longitudinally-open socket, and a knock-down lamp box carried by and arranged in rear of said frame and at its front edges coupled thereto by said means and comprising a back, flanged side plates removably fitting 40 the longitudinal edges thereof, and means arranged at the rear of said inclosure and removably holding the side plates to the back.

9. An illuminated sign consisting of a front display-sheet-receiving frame at its rear face 45 having side plate securing stops and back sockets, and a knock-down lamp inclosure consisting of a back having its ends fitting said sockets and removable side plates at their outer edges having flanges lapping the 50 side edges of said back and at their front edges having flanges fitting said frame and secured thereto by said stops, and means removably holding said side plates to said back.

In testimony whereof I affix my signature, 55
in presence of two witnesses.
